UNITED STATES PATENT OFFICE.

ALFRED HOPKINSON, OF CHESTER, ENGLAND.

BRAIDING-MACHINE.

1,204,982.

Specification of Letters Patent.

Patented Nov. 14, 1916.

Application filed January 20, 1914. Serial No. 813,239.

To all whom it may concern:

Be it known that I, ALFRED HOPKINSON, a British subject, residing at Chester, county of Chester, England, have invented certain new and useful Improvements in Braiding-Machines, of which the following is a specification.

This invention relates to braiding machines in which two rows or tiers of bobbins are mounted on rotary carriers or races revolving in opposite directions the threads of one set of bobbins being guided under and over the upper set of bobbins by suitable guide arms and the upper set of bobbins being driven by driving levers or pins which are caused to move in succession out of contact with the bobbin carrier to allow the thread to pass under it.

The invention consists in the special construction and arrangement of parts whereby the design of the machine is simplified.

The invention will be fully described with reference to the accompanying drawings.

Figure 1 is a front elevation. Fig. 2 is a plan. Fig. 3 is a longitudinal section when the bobbins are nearly over each other, on line V—V Fig. 2. Fig. 3^a is an enlarged detail of part of Fig. 3 showing fingers *d* and grooves *e*. Fig. 4 is a part section of same on line W—W Fig. 2. Fig. 4^a is an enlarged detail of part of Fig. 4 showing slide *g'*. Fig. 5 is a plan of bottom cam for operating swiveling arms. Fig. 6 is a side elevation of dish or bottom bobbin carrier. Fig. 7 is a part section of a modification showing one cam for driving the bobbins and also operating the swinging swiveling arms through an annular link arrangement on line X—X Fig. 10. Fig. 8 is a part section of same on line Y—Y Fig. 10. Fig. 9 is a longitudinal section of dish and annular link as shown in Figs. 7 and 10. Fig. 9^a is an enlarged detail of part of Fig. 9 showing cams *n*. Fig. 10 is a sectional plan of Fig. 7. Fig. 10^a is an enlarged detail of part of Fig. 10 showing lever *G²* and slot *b'*. Fig. 11 is a sectional view showing a detail of the modified construction disclosed in Figs. 7—10.

The machine is constructed with two rows or tiers of bobbins mounted upon suitable rotary carriers A and B which are rotated in opposite directions all mounted upon or around a central shaft or pillar C.

The lower bobbin carrier A is of dish shape with a sleeve or boss *a* mounted loosely

on the central pillar C and is rotated by a bevel wheel keyed thereto from a bevel on the driving shaft. The bobbins are preferably mounted upon vertical or approximately vertical pins *a'* carried in lugs or brackets *a²*.

The upper bobbin carriers B of which there is one for each bobbin are mounted upon an annular race *b* carried by or forming part of the lower bobbin carrier A. The race *b* rotates with the carrier A and the carriers B are rotated around it in the opposite direction. A number of recesses or indentations *b'* are made at intervals around the annular race *b* over which the carriers B successively pass to allow the thread *x* from each of the lower bobbins in succession to be passed behind the upper bobbins, and entwine with the threads *x'* therefrom.

The upper bobbin carriers B are rotated by a revolving cam ring or spider D carrying a number of sliding pins or fingers *d* which engage the carriers B and carry them forward around the race *b*. Two fingers *d* engage each bobbin carrier B and are withdrawn alternately at intervals to allow the lower thread *x* to pass, but one of the fingers *d* is always in engagement with the carrier to insure a continuous movement. The fingers *d* are moved in and out as required by a cam E provided with a groove or grooves *e* into which projections or pins *d'* on the driving pins or fingers *d* project. The fingers *d* thus slide direct into the bobbin carriers and are not pivoted as levers or blades. The spider D also carries a cam H for operating the thread guides G.

The revolving cam ring D is mounted by a sleeve or boss loosely on the upright pillar C and is rotated by a bevel wheel gearing with a bevel mounted on a stud at right angles to the upright pillar C and driven by another bevel on the boss *a* of the lower bobbin carrier A thereby giving the rotation in the reverse direction.

To the lower bobbin carrier A a number of guide eyes G are pivoted—one for each bobbin—to direct the threads *x* from each bobbin into the recesses *b'* in race *b* and around the upper bobbins. The guide eyes G are each formed on a swinging or swiveling arm *G'* which is caused to swing to and from the race *b* in approximately and preferably a horizontal plane, each swinging arm being connected by a link *g* with a slide *g'*. The slide *g'* is provided with pins or runners *g²*

which engage with the grooves h of the cam H by which the slides are moved to and fro as the lower bobbins are rotated. The cam H is carried by or forms part of the 5 revolving cam ring D and moves with it. The grooves h of the cam H may be varied in contour to vary the swinging of the guide arms G' according to the pattern or arrangement of the threads required in the 10 braiding. The cam H has two throws and the connecting link g may be pivoted to the arm G' at either the point g^3 or g^4 . If the arms G' are connected to the links alternately at the points g^3 and g^4 the arms will 15 work together and have the same movement, for the purpose of varying the pattern. If however all the arms are connected to the links at g^3 or at g^4 half of their number will move outward while the other half move 20 inward, the outwardly and inwardly moving arms being arranged in alternation. The thread α passes from the lower bobbin to a fixed guide eye g^5 in the underside of the pivot on which the arm swivels and thence 25 to the guide eye G.

In the arrangement shown in Figs. 7 to 10 the rotary lower bobbin carrier A' is constructed as previously described with the swiveling arms G² pivoted thereto. The 30 revolving cam ring D' is made with a single throw to the cam by which all the swinging arms are operated simultaneously. An operating ring K is mounted on the bobbin carrier A' which rotates with the carrier and to which a limited movement is given by the 35 cam in addition to its rotary movement. To the slide g^2 which is moved to and fro by the cam a bell crank lever M is connected by the link m and the lever M engages a pin k on the operating ring K. The inward or outward movement of the slide g^2 by the cam D' moves the ring K to and fro relatively to the carrier A while rotating with it. Each 40 of the swinging arms G² is connected by a link g^6 with the operating ring K, a pin k' at the end of the link engaging an inclined slot k^2 in the ring K. The rotation of the ring K on the bottom bobbin carrier A' consequently operates all the swinging 45 arms simultaneously and synchronously. 50

The ring K may be duplicated, both being operated by the same cam, one ring moving certain of the arms, and the other ring operated by a separate bell crank, moving the 55 remainder, to vary the pattern.

In substitution for the cam E of Figs. 1 and 2 the operating ring K carries a number of vertically moving cams N which are raised and lowered by the rotary movement 60 of the operating ring K by a pin n engaging an inclined slot or cam face n' in the edge of the ring. The sliding pins or fingers d^2 on the cam ring D' which engage with and carry around the top bobbin carriers on the race b^2 are moved out of engage-

ment with the carriers to allow the lower threads α to pass behind them,—by the cams N when they are raised by the movement of the operating ring K and are moved back into engagement with the bobbin carriers 70 by a spiral spring d^3 as clearly shown in Fig. 11.

The guide eye G at the end of the arm may be of any suitable shape and may be extended in the form of a tube or curved 75 guide plate to enter the recess or indentation b' in the annular race b and prevent the thread coming into contact therewith.

With the swinging arm G' or G², as the case may be, working on an inclined axis 80 symmetrically located relatively to the two positions of the guide arm and having the same angular relation to the thread in either position of said arm, the thread is uniformly tensioned by the guide arm in any position 85 thereof.

In operation the upper and lower bobbins revolve around the central pillar of the machine in opposite directions, the swinging guide arms G' or G² and thread eyes G 90 carry the threads α from the lower bobbin alternately—or as desired—behind the upper bobbins the threads α being carried into the recesses b' in the annular race b between the driving pins or fingers d , these pins or fingers being moved in and out to avoid the thread by the cam or cam surface with 95 which they engage.

What I claim as my invention and desire to protect by Letters Patent is:— 100

1. In a braiding machine, the combination of a cup-shaped carrier for a lower set of bobbins having an annular race thereon and provided with vertical slits, a set of upper carriers for an upper set of bobbins mounted to slide on said race, a cam, gearing for rotating said cam and said cup-shaped carrier in opposite directions, a plurality of driving pins for each carrier of said set slidably mounted on said cam, a stationary cam for controlling the projection and retraction of said pins, and vibratory thread guides operated by said rotatable cam for moving the threads of the lower bobbins in the slits of the cup-shaped carrier, said cup-shaped carrier inclosing both cams and the driving gearing for the rotatable cam. 110

2. In a braiding machine, the combination of a cup-shaped carrier for a lower set of bobbins, said carrier having an annular race thereon and being provided with vertical slits, a set of carriers for an upper set of bobbins mounted to slide on said race, a cam, gearing for rotating said cam and said cup-shaped carrier in opposite directions, a plurality of driving pins for each carrier of said set slidably mounted on said cam, a stationary post extending through said cup-shaped carrier and said cam, a stationary 115 120 125 130

cam fixed on said post for projecting and retracting said pins and vibratory thread guides operated by said rotatable cam for moving the threads of the lower bobbins in the slits of the carrier, said cup-shaped carrier inclosing both cams and the gearing for driving the rotatable cam.

3. In a braiding machine, in combination, a central vertical post, a cup-shaped carrier for a lower set of bobbins rotatably mounted on said post, driving means for said carrier, a set of carriers for an upper set of bobbins, vibratory thread guides mounted on said cup-shaped carrier for directing the threads of the lower bobbins relatively to the threads from the upper bobbins, a cam for operating said thread guides, gearing for driving said

cam from said cup-shaped carrier but in an opposite direction thereof, a plurality of driving pins for each carrier of said set 20 25 rotatably mounted on said arm, and a stationary cam for controlling the projection and retraction of said pins, the said cup-shaped carrier inclosing said rotatable cam and the gearing for driving the same.

In testimony whereof I have hereunto set my hand in presence of the subscribing witnesses.

A. HOPKINSON.
